(57) **CLAIM**

The ornamental design for a beverage dispenser, as shown and described.

DESCRIPTION

FIG. 1 is a perspective view of a beverage dispenser showing our new design;

FIG. 2 is a left side view of the beverage dispenser illustrated in FIG. 1;

FIG. 3 is a front view of the beverage dispenser illustrated in FIG. 1;

FIG. 4 is a right side view of the beverage dispenser illustrated in FIG. 1;

FIG. 5 is a rear view of the beverage dispenser illustrated in FIG. 1;

FIG. 6 is a top view of the beverage dispenser illustrated in FIG. 1; and,

FIG. 7 is a bottom view of the beverage dispenser illustrated in FIG. 1.

The broken lines depict portions of the beverage dispenser in which the design is embodied that are not considered part of the claimed design.
